UNITED STATES PATENT OFFICE.

HENRY B. JOY, OF DETROIT, MICHIGAN, ASSIGNOR, BY MESNE ASSIGNMENTS, TO
DELCO-LIGHT COMPANY, OF DAYTON, OHIO, A CORPORATION OF DELAWARE.

COMPRESSOR OR LIKE DEVICE.

Application filed December 24, 1917. Serial No. 208,627.

To all whom it may concern:

Be it known that I, HENRY B. JOY, a citizen of the United States, and resident of Detroit, Wayne County, State of Michigan, have invented certain new and useful Improvements in Compressors or like Devices, of which the following is a specification.

This invention relates to compressors or like devices where it is desirable to have a tight joint between a rotating shaft and the case or support which holds it. More particularly the invention relates to means for preventing leakage past a shaft bearing.

In the particular form in which the invention is herein illustrated (and this form is illustrative only) a two cylinder compressor is shown such as is used in connection with small refrigerating units for compressing the refrigerant, the compressor including a crank case, and a crank shaft journaled in bearings in the wall thereof and having one end extending through the wall of the crank case for transmitting power into the interior thereof. In such cases the refrigerant is usually drawn into the crank case of the compressor and then by-passed to the cylinders and there compressed. It is important therefore that the crank case shall be both fluid and gas tight. It is one of the objects of the present invention to produce a structure that will obtain such tightness of the crank case and maintain it through a long period of operation of the compressor.

Other objects of the invention will appear from the following description taken in connection with the drawings which form a part of this specification, and in which:

Fig. 1 is a vertical sectional view of a compressor embodying the invention;

Fig. 1^a is a section illustrating another form of the joint between the crank shaft and the casing;

Fig. 2 is an enlarged detail section of the floating ring shown in Fig. 1 and is on the line 2-2 of Fig. 3;

Figs. 3 and 4 are side views of said ring;

Fig. 5 is an enlarged detail section of a bearing ring forming part of the joint shown in Fig. 1; and

Figs. 6 and 7 are side views of the ring shown in Fig. 5.

In small compressors for refrigerating apparatus of the household type, such as that illustrated and in which the power is transmitted through a rotary shaft passing

through the wall of the crank case, great difficulty has been experienced in preventing leakage of gas along the shaft, owing to the short bearings formed in such small machines, the bending of the crank shaft when the compressor stops under compression even though the crank shaft is originally perfectly machined, the assumption of a permanent bend in the crank shaft as it ages, and for other reasons. The prevention of such leakage, however small, becomes a matter of prime importance in the successful operation of household refrigerators owing to the fact that the latter are intended for installation in isolated places and for operation without the care of an attendant. The present invention contemplates overcoming this difficulty by providing the crank case and crank shaft with interfitting sealing means having cooperating ground surfaces so mounted, constructed and arranged as to seal the casing under all conditions of alignment and misalignment of the shaft in its bearings, there being spring means for thrusting the entire shaft endwise and to force the cooperating ground surfaces together.

Referring to the drawings, 10 represents the crank case and 11 the cylinders of a compressor or similar device. The compressor here illustrated is of the type used in connection with small refrigerating units for compressing the refrigerant. The crank case is mounted upon a stand 12 which in this instance also forms the bottom cover of the crank case. One end of the crank case is formed with an opening 13 over which is a detachable cover 14 secured to the crank case as by bolts 15.

The cover 14 also has an opening entirely therethrough and forms a relatively short bearing 16 for the crank shaft 17 of the compressor. The crank shaft has two crank pins 18 upon which are mounted the large ends of the connecting rods 19, on the lower ends of which are scoops 20 which are adapted to dip into the lubricant in the bottom of the crank case and thus carry the lubricant directly to the crank pins 18 and by splash to the other bearings within the crank case. As shown, the other end of the crank shaft is mounted in a bearing 21 formed in the crank case, and the crank shaft end is drilled out to form a socket 22 in which is a sliding member 23 and a

spring 24 which holds the sliding member against a steel disk 25 at the end of the bearing 21. By this means it will be seen that the crank shaft is yieldingly pressed toward the left in Fig. 1 for a purpose that will be hereinafter described.

The bearings 16 and 21 are fed with lubricant by splash from the crank case through openings 26 and 27 respectively.

10 The crank case is also provided with an inlet opening 28 through which the refrigerant enters to be bypassed to the cylinder.

The crank shaft 17 extends entirely through the bearing 16 in which it is supported, and this extending end 29 is connected to a pulley 30 or other driving device, as by the key 31 and nut 32 and the crank shaft is thus given its rotary driving movement.

15 20 The extended end 29 of the crank shaft is shown somewhat contracted in size relative to the part 33 which operates in the bearing 16, so that a shoulder 34 is formed between the two parts 29 and 33. For the 25 purposes of this invention this shoulder 34 is preferably in an exact transverse plane relative to the axis of the crank shaft, and it is found best to make it a ground surface.

25 30 The support or crank case, or that part of it comprising the bearing 16, is provided with a part 35 which is shown in the form of a threaded detachable ring surrounding the contracted part 29 of the crank shaft.

35 40 The crank shaft passes loosely through this ring 35 and between the shoulder 34 of the crank shaft and this ring 35 there is arranged a ring 36 which is preferably a floating ring, or, in other words, the ring 36 is not connected to either the crank shaft or its support. This ring 36 which is shown in detail in Figs. 2, 3 and 4 has a plane surface 37 which is transverse to its axis and which is adapted to co-operate with the 45 plane surface 34 of the shoulder of the crank shaft 33 and this surface 37 is likewise preferably ground so that there may be a very nice fit between it and the surface 34.

The ring 36 and the ring 35 are formed 50 with co-operating surfaces of a character that will permit of some slight misalignment of the shaft relative to its support without separation of these surfaces. As shown, these surfaces are spherical in form and the 55 radius of the sphere to which these surfaces conform is sufficiently great to warrant close contact between the surfaces as the crank shaft is pressed yieldingly in an axial direction. This pressure is constantly maintained by the spring 24 hereinabove referred to, or equivalent means, and it has been found that the radius of the sphere above referred to should be approximately the same as or greater than the diameter of the part of the shaft which is surrounded by

the ring 36, or, in other words, greater than the inner diameter of the ring 36. This is probably best illustrated in Fig. 2 where the radius a of the spherical surface 38 of the ring 36 is shown to be approximately 70 the same, though a little greater than the inner diameter b of the ring 36. It has been found that where a much smaller radius is used or something different from a spherical surface is employed, the rings are liable to 75 be wedged into each other or to be thrown out of alignment whereas these things do not occur with the ring shown in this application.

The ring 35 is also shown in detail in 80 Figs. 5, 6 and 7 and it will be understood that its contact surface 39 also conforms to a sphere the radius of which is exactly the same as that of the surface 38. Thus, in Fig. 5 the radius a is the same as the radius 85 a of Fig. 2. It will be understood further that the surfaces 38 and 39 are preferably ground surfaces for the purpose of making a very nice fit between them, and in fact the fit between these two surfaces and the two 90 plane surfaces 34 and 37 form practically a sealing contact so that as the surfaces are yieldingly pressed together there is actually no leakage past them even though they 95 rotate on each other.

For the purpose of assisting this sealing action and preventing friction between the contacting surfaces, means are provided for supplying a lubricant to the surfaces and, as shown, these means are contained in the 100 ring 36. Thus, the ring 36, as shown in Figs. 2, 3 and 4, has each of its contacting surfaces drilled with a series of recesses 40 which may be filled with graphite or similar lubricating material. Preferably 105 these recesses are drilled on a circle eccentric to the center of the ring, as shown by the dotted ring 40^a in Fig. 4 so that the graphite may be distributed to all parts of the 110 surface.

The ring 35 is shown as threaded into the cover 14 and is withdrawable by the use of a spanner operating in the holes 41 in the outer surface of the ring.

Under most circumstances the graphite 115 supplied to the contacting surfaces by the ring 36 will be sufficient for all purposes, but in other cases it is found desirable to further supply the contacting surfaces of the ring 36 with lubricant. In the present instance the cover 14 is formed with a pocket 42 for a liquid lubricant of some kind and a ring 43, somewhat larger than the part 29 of the crank shaft, is hung on the shaft so that the ring dips in the lubricant in the pocket 42. This supplies lubrication in small quantities to the contracted part of the crank shaft and it finds its way along the shaft to the ring 36 where it reaches the contacting surfaces thereof. 120 125 130

The outer end of the cover 14 is closed by a cap 44 which surrounds the end of the crank shaft and is threaded into the cover 14. There is also a throw-off ring 45 on the crank shaft which is inside of the cap 44 which prevents the oil fed to the shaft from passing outwardly along the shaft. An oil opening 46 with a removable cap 47 permits the pocket 42 to be refilled.

10 In the form of the invention shown in Fig. 1^a the part 14^a of the crank case which forms the bearing for the crank shaft is formed with a plane surface 34^a which is preferably ground and is in a plane exactly 15 transverse to the axis of the bearing 16 and is therefore parallel to the plane of the shoulder 34. In this form also, the ring 35^a is not threaded into the crank case but is formed with a plane surface 34^b which 20 rests against the surface 34^a on the crank case part. The ring 35^a is held in contact with said surface 34^a by a locking ring 35^c which preferably contacts only with the outer circumference of the ring 35^a so that 25 the latter ring is fitted nicely against the surface 34^a.

By the above arrangement parallelism of the rings 36 and 35^a is insured regardless of the accuracy of the threading in the 30 crank case part.

Other forms may be used without departing from the spirit or scope of my invention.

Having thus described my invention, 35 what I claim and desire to secure by Letters Patent is:—

1. A compressor for refrigerating apparatus of the household type comprising a cylinder, a piston operable in the cylinder, a crank casing adapted to receive therein the refrigerant to be compressed, said crank casing having a relative short bearing formed in one wall thereof, a rotatable crank shaft having one end thereof 40 supported in said bearing and extending through the wall of the crank casing, means connecting the piston and the crank shaft, said casing wall being provided axially outward of and adjacent to said bearing with a bearing member surrounding the shaft and having a spherical surface, a shoulder on said shaft adjacent said bearing member, and a floating ring surrounding the shaft and in direct contact 45 with said shoulder and the bearing member, said ring having a spherical surface to fit the spherical surface of the bearing member, the radius of said spherical surfaces approximating the diameter of the crank 50 shaft at said ring.

2. A compressor for refrigerating apparatus of the household type, comprising a cylinder, a piston operable in the cylinder, a crank casing adapted to receive therein 55 the refrigerant to be compressed, said crank

casing having a relative short bearing formed in one wall thereof, a rotatable crank shaft having one end thereof supported in said bearing and extending through the wall of the crank casing, means connecting the piston and the crank shaft, said crank shaft having a contracted part forming a transverse shoulder on the shaft adjacent to said bearing, a ring surrounding the contracted part of the shaft and in direct bearing contact with said shoulder, and a second ring detachably connected to the crank casing in engagement with the first ring, the engaging surfaces of the two rings being spherical and of a radius greater than the diameter of the shaft.

3. A compressor for refrigerating apparatus of the household type comprising a cylinder, a piston operable in the cylinder, a crank casing adapted to receive therein the refrigerant to be compressed, said crank casing having a relative short bearing formed in one wall thereof, a rotatable crank shaft having one end thereof supported in said bearing and extending through the wall of the crank casing, means connecting the piston and said crank shaft, said casing and said shaft each being formed with transverse plane shoulders, the planes of said shoulders being parallel, two rings surrounding said shaft and having cooperating spherical faces, said rings also having plane faces in engagement with the respective plane shoulders on said casing and said shaft.

4. A compressor for refrigerating apparatus comprising a bearing member, a shaft member and a floating ring on the shaft member bearing against both members in a generally axial direction, said ring having recesses in its bearing surfaces for graphite or other lubricant, and said recesses being disposed in a circular series eccentric to the axis of the ring.

5. A compressor for refrigerating apparatus of the household type comprising a casing having a cylindrical bore through its wall forming a relatively short bearing, the axially outer portion of said bore being counterbored forming a shoulder, a shaft within said case extending outside thereof and having a part rotatably supported by said bearing, the section of the shaft projecting from said bearing being of reduced diameter forming a shoulder, a packing ring loosely surrounding the reduced shaft section and bearing against said shaft shoulder, a second ring bearing against said first ring, the outside diameter of said second ring being greater than the first, the contacting surfaces of said rings being spherical, and means holding said second ring against the first mentioned shoulder.

6. A compressor for refrigerating apparatus of the household type having a closed

casing formed at each end with a hollow boss and at one side with one or more cylinders, one of said bosses being cast integral with the casing and completely closed 5 to the exterior and the other having an aperture therethrough to provide relatively a short shaft bearing surrounded by a shoulder, a bearing ring clamped against said shoulder and having a spherical working 10 face presented inwardly, a shaft journaled in said bosses and projecting through said aperture, a sealing ring carried by said shaft and engaging said bearing ring, a connecting rod operatively connected to said shaft 15 and projecting into said cylinder, a spring inside the closed boss and forcing said shaft endwise so as to hold said bearing ring and sealing ring together, and driving means connected to the protruding portion of said 20 shaft.

7. A compressor for refrigerating apparatus of the household type comprising a casing having shaft bearings formed therein, a shaft member journaled in said bearings 25 and having a crank integral therewith, one end of said shaft member projecting through the casing wall and provided with an annular shoulder having a bearing surface thereon, the shaft bearing for the projecting 30 end of said shaft member being relatively short, interfitting sealing means between the shoulder and the adjacent wall of the casing so constructed and arranged as to seal the casing during all conditions of alinement or 35 misalinement of the shaft in its bearings, said sealing means including a shoulder formed in the casing wall and having a spherical bearing surface concentric with the shaft member, a bearing ring member 40 interposed between said shoulders and having bearing surfaces cooperating with and conforming with the bearing surfaces on said shoulders, and spring means within the casing and interposed between the casing 45 and one end of the shaft member to thrust the entire shaft member endwise and to force said bearing surfaces together.

8. A compressor for refrigerating apparatus of the household type comprising a

casing having shaft bearings formed therein, 50 a shaft member journaled in said bearings and having a crank integral therewith, one end of said shaft member projecting through the casing wall and provided with an annular shoulder having a bearing surface 55 thereon, the shaft bearing for the projecting end of said shaft member being relatively short, interfitting sealing means between the shoulder and the adjacent wall of the casing so constructed and arranged as to seal the 60 casing during all conditions of alinement or misalinement of the shaft in the bearings, said sealing means including a bearing ring member surrounding the shaft member and having a bearing surface in engagement 65 with said first-mentioned bearing surface and spring means within the casing and interposed between the casing and one end of the shaft member to thrust the entire shaft member endwise and to force said bearing 70 surfaces together.

9. A compressor for refrigerating apparatus of the household type comprising a casing having shaft bearings formed therein, 75 a shaft member journaled in said bearings and having a crank integral therewith, one end of said shaft member projecting through the casing wall and provided with an annular shoulder having a bearing surface thereon, the shaft bearing for the projecting end of 80 said shaft member being relatively short, interfitting sealing means between the shoulder and the adjacent wall of the casing so constructed and arranged as to seal the casing during all conditions of alinement or 85 misalinement of the shaft in the bearings, said sealing means including a bearing ring member surrounding the shaft member and having a bearing surface in engagement with said first-mentioned bearing surface, and spring means introduced between one of 90 said members and a part of the casing tending to automatically thrust the entire shaft member endwise and to force said bearing surfaces together.

In testimony whereof I affix my signature.

HENRY B. JOY.
